UNITED STATES PATENT OFFICE.

JAMES F. CUMMINGS, OF DETROIT, MICHIGAN, ASSIGNOR TO THE AMERICAN VITRIFIED CONDUIT COMPANY, OF NEW YORK, N. Y.

TOOL FOR LAYING CONDUITS FOR ELECTRICAL CONDUCTORS.

SPECIFICATION forming part of Letters Patent No. 644,794, dated March 6, 1900.

Application filed July 22, 1899. Serial No. 724,777. (No model.)

To all whom it may concern:

Be it known that I, JAMES F. CUMMINGS, a citizen of the United States, residing at Detroit, in the county of Wayne and State of Michigan, have invented certain new and useful Improvements in Tools for Laying Conduits for Electrical Conductors, of which the following is a specification, reference being had therein to the accompanying drawings.

10 The invention relates to tools for laying tile conduits for electrical conductors.

It is the object of the invention to secure a more accurate alinement of the conduit-sections with each other and to remove the 15 cement which passes through the joint between the sections, so that the interior of the conduit when finished will be smooth and unbroken.

In the laying of tile conduits for the purpose described it is customary to embed the sections in cement. To secure accurate alinement of each of the sections, it is necessary to employ a tool or mandrel which bridges the joint between the sections and holds them 25 in proper relation. These tools as heretofore made consist of an elongated body of substantially the bore of the conduit, being provided with a handle at its forward end for drawing it through the conduit-section. The 30 objection to such construction is that in the use of the tool the wear of the body soon reduces its diameter, so that it no longer accurately fits the bore of the conduit-sections, and consequently the latter are not accurately 35 alined.

It is one of the objects of my invention to provide means whereby the tool may be maintained the proper size, and, further, to provide means for more thoroughly cleaning the 40 joint between sections.

The invention therefore consists in the construction, arrangement, and combination of parts, as hereinafter more fully described and claimed.

45 In the drawings, Figure 1 is a vertical longitudinal section through a conduit, showing in elevation my tool as in use therein. Fig. 2 is a cross-section on line xx , Fig. 1. Figs. 3, 4, and 5 are views similar to Fig. 1, showing modifications.

As shown in Figs. 1 to 4, my tool comprises,

essentially, a central stem A and a surrounding helix B, secured at its opposite ends to said stem and adapted to fit the bore of the conduit. This structure may be formed either 55 as shown in Figs. 1 and 3, where the stem and helix are bent from a single rod, or as shown in Fig. 4, where they are formed from separate rods. With both constructions the stem serves to hold the coils of the helix in alignment with each other, or, in effect, to produce a cylindrical body which is of a diameter to fit the conduit and preferably of a length somewhat greater than that of one of the conduit-sections.

65 With the tool constructed as thus far described in the operating of laying the conduit the tool is placed in one of the conduit-sections, which is then laid in position in the cement. Other sections are then laid successively, and as each new one is placed in position the operator draws the tool along.

70 It will be readily understood that as the diameter of the helix is such as to fit the bore of the conduit-sections the latter will be 75 brought into alinement by the drawing of the tool past the joint. At the same time each convolution of the helix acts as a scraper which wipes the joint between the conduit-sections and removes any cement on the surface.

75 In order to provide means for drawing the tool through the conduit, I preferably form an eye C at one end of the stem, and to facilitate the passage of the helix from one section to another the forward end convolutions thereof are preferably of a spiral form, thus 80 making a tapering nose to the helix.

In Figs. 3 and 4 I have shown a construction in which a brush D is placed upon the 90 stem between two sections of the helix, which brush forms an additional wiper for the joint. The two sections of the helix are, in the construction shown in Fig. 3, formed of a single rod, of which the central portion forms the 95 stem and the end portion of the helices.

In Fig. 5 I show a construction in which the tool is composed of a central stem A and a series of disks E, secured thereon and spaced from each other by the intermediate sleeves 100 or collars F, the parts being secured in position by a clamping-nut G at the end of the

stem. In this construction, as in those previously described, the disks form a series of spaced scrapers fitting the bore of the conduit and serving to both aline the sections and wipe the joint.

5 What I claim as my invention is—

1. A tool for laying conduit for electrical conductors comprising a central stem and a non-collapsible alining and scraper helix 10 rounding and fixedly secured to said stem of a size to fit the bore of the conduit.

2. A tool for laying conduits for electrical conductors comprising a central stem and a surrounding helix formed of a single rod substantially as and for the purpose described.

15 3. A tool for laying conduits for electrical conductors, comprising a central stem, two

helices surrounding said stem and a brush arranged on said stem between the helices substantially as and for the purpose described.

4. A tool for laying conduit for electrical conductors comprising a central stem and a series of surrounding scraper-surfaces having their opposite portions spaced from and 20 in alinement with each other and adapted to fit the bore of the conduit.

In testimony whereof I affix my signature in presence of two witnesses.

JAMES F. CUMMINGS.
